RANGE TOP

Eugene Stoligrosz and Delbert R. Easton, both of Hamilton, Ohio, assignors to Whirlpool Corporation, a corporation of Delaware

Filed Jan. 11, 1962, Ser. No. 163,521
3 Claims. (Cl. 126—39)

This invention relates to heating means and in particular to burner means for use in gas ranges.

In one form of improved gas range, a drop-in cooktop is arranged to be placed in a suitable opening in the countertop of a kitchen cabinet. The present invention is concerned with the provision of an improved gas burner and cooktop structural combination for use in such countertop installations.

Thus, a principal feature of the present invention is the provision of a new and improved gas burner-cooktop structure.

A further feature of the invention is the provision of such a structure wherein the burner is arranged as an atmospheric burner.

A still further feature of the invention is the provision of such a structure having new and improved means for preventing spillage from passing downwardly to below the cooktop.

Still another feature of the invention is the provision of such a structure having new and improved means for providing air to the burner flame.

A yet further feature of the invention is the provision of such a structure wherein the air delivered to the burner flame sweeps across a portion of the burner body and the cooktop to cool the same.

A further feature of the invention is the provision of new and improved means for sealingly mounting the burner on the cooktop to preclude leakage therethrough.

Other features and advantages of the invention will be apparent from the following description of certain embodiments thereof taken in connection with the accompanying drawings. Of the drawings:

FIGURE 1 is a fragmentary top plan view of a gas range structure embodying the invention.

FIGURE 2 is a vertical section thereof taken substantially along line 2—2 of FIGURE 1.

FIGURE 3 is a fragmentary vertical section of a modified form thereof.

FIGURE 4 is a fragmentary vertical section of another modified form thereof.

FIGURE 5 is a fragmentary vertical section of still another modified form thereof.

FIGURE 6 is a fragmentary vertical section of yet another modified form thereof.

In exemplary embodiment of the invention as shown in FIGURES 1 and 2 of the drawings, a gas range generally designated 10 is shown to include a gas burner generally designated 11 and a cooktop generally designated 12 through which the burner is arranged to extend. The cooktop is arranged to be installed on a countertop 13 having a suitable opening 14 therein. A conventional burner box 15 is associated with the cooktop 12 and is similarly installed on the countertop 13 to extend below the cooktop 12 and burner 11 carried thereon.

More specifically, the burner 11 includes an annular body 16 comprising a hollow wall provided with a plurality of burner ports 17 at its upper end 18 and closed at its upper end by a suitable cap 19. Thus, the body wall defines an interior flow passage 20 and a central axial flow passage 21. Combustible fuel such as gas is delivered to the flow passage 20 by a suitable inlet 22 connected to a conventional supply (not shown) for delivery through the flow passage to the ports 17 to provide a plurality of flames F extending generally laterally outwardly

2

from the ports 17 at the upper end 18 of the burner body. The gas delivered from inlet 22 may be premixed with a suitable quantity of primary air. However, additional secondary air is provided to the flames F both below and above the flames as shown by the arrows in FIGURE 2.

More specifically, cooktop 12 is provided with a plurality of air inlet openings 23 in a peripheral depending flange portion 24 thereof. Air flows through openings 23 downwardly through the space 25 between the cooktop 12 and the burner box 15 and thence upwardly through the central passage 21 of the burner body to the upper end 18 thereof. A deflector 26 is installed on the burner body to overlie the upper end of the passage 21 and deflect the air therefrom laterally outwardly over the burner body cap 19. Thus, deflector 26 serves both to deflect the secondary air from passage 21 to the flames F and to prevent spillage of food matter and the like from passing downwardly through the passage 21. As shown in FIGURE 2, the deflector preferably extends laterally sufficiently to overlie the burner body cap 19 thereby effectively precluding the dropping of such matter onto any portion of the burner body and, more specifically, onto the ports 17 thereof.

A second stream of air, as shown in FIGURE 2, is delivered to the flames F after flowing over the upper surface of the cooktop 12. As shown in FIGURE 2, the cooktop is provided with a depressed portion 27 effectively defining an annular well or sump circumjacent the burner body 16 which is adapted to collect dropped matter and spillage. The depressed portion 27 includes a generally frusto-conical inner portion 28 extending generally toward the flames F and thereby guiding the air flowing downwardly through the well 27 upwardly therefrom toward the flames to provide improved secondary air delivery thereto. As a result of the improved secondary air delivery, an even blanket of flame is provided by the burner 11 for improved facilitated cooking and the like with the range 10. Thus, a uniform distribution of the hot gases is provided to the under surface of a receptacle or the like (not shown) placed on the conventional grates 29 disposed above the burner 11.

The invention further comprehends an improved mounting of the burner on the cooktop providing facilitated installation and maintenance of the range. More specifically, as shown in FIGURE 2, the burner body is provided with an annular downwardly facing shoulder 30 immediately below the ports 17. The cooktop portion 28 terminates inwardly in a slightly turned frusto-conical section 31. An annular support 32 encircles the burner body 16 and includes an outer portion 33 removably resting on the cooktop section 31 and an inner portion 34 engaging the shoulder 30 to removably carry the burner body thereon. The outer portion 33 of the support 32 is preferably frusto-conical similar to the cooktop portion 28 and defines a continuation thereof to guide the air directly to the flames F closely adjacent the upper end of the support 32. The support 32 is further arranged to seal the burner body to the cooktop thereby effectively precluding passage of dropped matter and spillage through the central opening 35 defined by the cooktop section 31 through which the burner extends. As the support portion 33 and the cooktop section 31 widen frusto-conically downwardly toward the sump portion 27 of the cooktop, such dropped matter and spillage is caused to drop into the sump and is effectively precluded from passing downwardly through the opening 35 onto the burner box 15. Still further, the air flowing through space 25 is effectively precluded from being diverted upwardly through the opening 35 and assures effectively positive delivery thereof through the passage 21 for deflection by the deflector 26 to the space directly above flames F.

The deflector 26 may be removably installed on the

burner body 16 by suitable legs 36 provided with tabs 37 at their lower ends releasably snapping into openings 38 in the burner cap 19. Thus, the deflector 26 may be readily separated from the burner for facilitated maintenance when desired.

The annular support 32 may be formed of a suitable heat resistant material and herein the support 32 is die cast of aluminum. The support 32 comprises a split annular structure for facilitated installation.

As discussed above, the burner 11 is arranged for improved facilitated maintenance. As the burner body merely rests on the support 32 and the support 32 in turn merely rests on the cooktop section 31, the removal of the burner body for maintenance is readily effected simply by removing deflector 26, removing cap 19 and lifting the burner body upwardly through the opening 35. The split annular support 32 may then be removed by simply lifting it upwardly allowing the split 32a to expand so that support 32 will slip over shoulder 30 of body 16. This allows body 16 to drop through opening 35 and cooktop section 31 may be removed to service the burner 11. The sump 27 is readily maintained simply by wiping it clean without the necessity of removing the burner 11. The rounded configuration of the sump thusly permits facilitated maintenance while at the same time providing the desirable smooth air flow therethrough and upwardly to the flames F.

As best seen in FIGURE 2, burner cap 19 may be provided with a radially outwardly projecting peripheral portion 39 extending substantially laterally from the upper end 18 of the burner body 16 to assist the deflector 26 in effectively precluding the dropping of matter and spillage onto the ports 17.

Turning now to FIGURES 3 through 6, modified forms of the burner structure embodying the invention are illustrated. In each of the modified forms, the distinction thereof from the burner 11 resides in the arrangement of the support and the associated portion of the burner body and cooktop. Thus, in FIGURE 3, a burner generally designated 111 is shown to comprise a burner generally similar to burner 11 but having a support 132 provided with an outer portion 133 having a lower surface 134 facially engaging the inturned section 131 of the burner box 112. The angularity of cooktop section 131 to the vertical axis of the burner is substantially greater than the angularity of cooktop section 31 to the axis of burner 11 and the inner section 134 of the support 132 is correspondingly thinner to accommodate the increased radial extension of the cooktop section. The other portions of burner 111 are generally similar to those of burner 11 and the burner 111 functions similarly.

Referring now to FIGURE 4, a burner 211 is shown to include a burner body 216 having a modified upper end 218 including a downturned frusto-conical portion 240 extending substantially downwardly to the level of the bottom of the sump 227 of the cooktop 212. The support 232, preferably a resilient heat resistant rubbery material, in burner 211 includes an upper portion 233 having a frusto-conical inner surface 234 sealingly resting on the lower end of the frusto-conical body portion 240. The support 232 is further provided with a radially outwardly opening groove 235 sealingly receiving the peripheral edge 236 of the cooktop defining the inner opening 237 thereof. Cap 219 is provided with flame ports 217. In all other respects, burner 211 is similar to burner 11 and functions in a similar manner.

In FIGURE 5, a modified burner 311 is shown to include a support 332 having a radial lower surface 333 sealingly resting on a radially inturned cooktop section 331. The upper end 318 of the burner body 316 includes a radially out-turned flange 330 resting on the upper surface 334 of the support 332. A cap 319 generally similar to cap 219 of burner 211 is provided at the upper end of the burner body 318 and includes the burner ports 75

317. Burner 311 in all other respects is similar to burner 11 and functions in a similar manner.

Referring now to FIGURE 6, a modified burner 411 is shown to include a support 432 generally similar to support 132 of burner 111. Burner 411 differs from burner 111 in the provision of a cap 419 generally similar to caps 219 and 319 and provided with the flame ports 417. Burner 411 is generally similar in all other respects to burner 11 and functions in a similar manner.

Thus, in each of the burner structures 111, 211, 311 and 411 an improved burner structure is provided wherein the burner body is readily removable from the cooktop while yet the burner is effectively sealingly carried on the cooktop for preventing passage of spillage and the like downwardly through the cooktop and for improved delivery of the secondary air to the burner flames. In each of the modified forms of the invention, an improved facilitated maintenance of the cooktop itself is provided as a result of the provision in the cooktop of the spillage collecting sump portion circumjacent the burner. In each of the different disclosed forms of the invention an improved cooling sweep of air is provided over the cooktop and upper end of the burner and in each an improved uniform blanket of flame is obtained by the improved secondary air delivery to the upper end of the burner.

Having described our invention as related to the embodiments shown in the accompanying drawings, it is our intention that the invention be not limited by any of the details of description, unless otherwise specified, but rather be construed broadly within its spirit and scope as set out in the accompanying claims.

The embodiment of the invention in which an exclusive property or privilege is claimed is defined as follows:

1. A range top structure comprising: a burner including an annular body defining a hollow wall provided with an upper end having burner ports; means for delivering combustible fuel through said hollow wall to said ports to provide a flame extending outwardly from said ports; a cooktop having an upwardly narrowing frusto-conical deflector portion circumjacent said wall and having an upper portion spaced below said upper end of the burner body; and an annular support encircling the burner body subjacent said ports and having a lower, first portion 40 removably supported on said upper portion of the cooktop deflector and an upper, second portion removably supporting said burner body, said support being arranged to seal the cooktop to the burner body to preclude substantial air leakage and passage of dropped matter therebetween and defining an outer annular surface extending upwardly from said cooktop deflector to subjacent said burner ports, said upper portion of the cooktop deflector and said lower portion of the support having substantially the same diameter whereby said deflector and support 45 define a substantially regular guide surface for guiding air flow smoothly upwardly from said cooktop to said ports.

2. The range top of claim 1 wherein said support outer surface is frusto-conical narrowing upwardly.

3. The range top of claim 1 wherein said support is formed of a thermally conductive material such as aluminum.
